UNITED STATES PATENT OFFICE

2,648,503

TAKE-UP BLOCK FOR WIRE DRAWING

Daniel Revak, Donora, and Frederick W. Riedel,
Belle Vernon, Pa., assignors to United States
Steel Corporation, a corporation of New Jersey

Application April 17, 1951, Serial No. 221,488

2 Claims. (Cl. 242—72)

1

This invention relates to a take-up block for drawing wire through processing apparatus and winding it in coils and, in particular, to a block having a collapsible core or barrel.

It is the object of our invention to improve on the block disclosed in Proctor Patent No. 2,529,185 and particularly to produce a block of simplified construction specially adapted for forming the smaller sizes of wire coils.

In a preferred embodiment of our invention, we provide a mandrel having spaced side plates, one fixed thereon and one removable therefrom. The mandrel is mounted on the end of a drive shaft. A plurality of separate segments extend between the side plates forming a cylindrical core for a coil wound between the plates. The segments have internal frusto-conical surfaces at their ends adapted to engage similar surfaces on the side plates, whereby limited radial movement may be imparted to the segments to contract or expand the coil core formed thereby. The end of the mandrel is threaded to receive a nut which presses the removable side plate toward the fixed side plate and thereby forces the segments outwardly. The segments are loosely held on the mandrel by a retainer ring secured thereto and are keyed to the mandrel to insure rotary movement therewith.

A complete understanding of the invention may be obtained from the following detailed description and explanation which refer to the accompanying drawings illustrating the present preferred embodiment. In the drawings,

Figure 1 is a side elevation;

Figure 2 is an end elevation;

Figure 3 is an axial section showing parts in elevation;

Figures 4, 5 and 6 are transverse sections taken along the planes of lines IV—IV, V—V, and VI—VI, respectively, of Figure 3; and

Figure 7 is a partial longitudinal section through one of the segments.

Referring now in detail to the drawings, the block of our invention, indicated generally at 10, comprises a mandrel 11, including a hollow hub 11a and a tubular spindle 11b. The latter is adapted to receive the free or overhanging end of a shaft 12. The shaft is journaled in suitable supporting bearings (not shown) and driven by any convenient source of power. The hub 11a of the mandrel has bearing bushings 13 pressed thereinto whereby the mandrel is journaled on the shaft and may be held stationary while the shaft continues to rotate.

A friction clutch 12a is carried on shaft 12, adapted to cooperate with the interior surface 55

2

of the hub 11a for driving the mandrel when desired. The mandrel is held on shaft 12 by a thrust collar 14 fitting in a recess 15 in the outer or free end of the spindle 11b and secured to the shaft by a set screw. Access to the screw is afforded by a radial hole drilled through the spindle wall. The outer end of the spindle is threaded for a short distance inwardly of the recess 15.

Hub 11a of the mandrel is turned down to form a step 11c adjacent the spindle, leaving a shoulder 16. The edge of the step, furthermore, is beveled as at 17. Hub 11a has inclined slots 18 milled therein at 90° intervals around the circumference. Quadrant plates 19 are welded to shoulder 16 so that radial spaces or slots 20 are left between adjacent plates in alignment with slots 18. Stiffening ribs 21 spaced circumferentially of the hub are welded thereto and to the quadrant plates. The inner edges of the quadrant plates overhang the beveled edge 17 of the step 11c and form therewith a circumferential groove, the inner wall of which is the edge 17. The quadrant plates 19 together form an inner side plate for the block which confines successive layers of turns of the coil wound thereon, and will hereafter be referred to as such. The side plate 19 is rigid with the mandrel and turns or stands still with it.

An outer side plate 22 having a central bore is removably disposed on the free end of the spindle, being held thereon by a nut 23 screwed on the threaded end of the latter. The nut has circumferentially spaced radial holes 24 to accommodate a spanner. The side plate 22 has radial slots 25 at 90° intervals. A key 26 in a keyway on the tubular portion 11b of the mandrel cooperates with keyways in the central bore of side plate 22 and insures that the latter, when placed on the spindle, will have its radial slots 25 in alignment with the spaces or slots 20 of side plate 19. The inner face of side plate 22 has a circumferential groove 27, the inner wall of which is frusto-conical. A plurality of cylindrical segments 28 extend between the side plates 19 and 22 and form a core or barrel upon which a coil may be wound. The segments have ends of frusto-conical shape on the interior, adapted to engage beveled edge 17 and the inner wall of groove 27. The effect of this cooperation, of course, is to cause outward radial movement of the segments as side plate 22 is moved toward side plate 19. Conversely, when side plate 22 is removed, the segments 28 are permitted to collapse, thereby facilitating the removal of a coil of wire wound thereon.

The segments 28 are keyed individually to the

tubular portion 11b of the mandrel as at 29. This insures rotary movement of the segments with the mandrel. The outer surfaces of the segments have longitudinal slots 30 therein in alinement with slots 18, 20 and 25. Nut 23 has circumferentially spaced recesses 31 which aline with these slots when the nut is turned home tightly. The slots and the recesses permit wire ties to be placed around a coil wound on the segments, at 90° intervals, before the coil is removed from the block. The segments 28 have arcuate slots 32 around the interior thereof opening toward one end. A ring 33 fitted on the spindle 11b and secured to it by set screws, has an overhanging flange or lip 34 at its inner side which enters the slots 32 in the segments 28 and loosely confines the latter in position about the mandrel. There is sufficient play, however, between the lip and the walls of the slots to permit the limited radial and longitudinal movement of the segments incident to the outward movement and collapse thereof described above. The outer ends of the segments have circumferentially spaced radial slots 28a therein.

The operation of our block will doubtless be readily apparent from the foregoing but will be reviewed briefly. It will be assumed that the shaft 12 is being driven, that the clutch for driving the block is disengaged so that the block is stationary, and that nut 23 and outer side plate 22 are disposed on the mandrel with the nut turned home tightly. The end of a length of wire being processed as by being drawn through a reducing die is attached to one of the segments 28 by inserting its end through one of the slots 28a and bending it over. The clutch is then operated to cause the block to be driven whereupon it winds up the wire on segments 28 in successive layers extending between the side plates. The segments 28, of course, when in their outermost positions, form substantially a complete cylinder serving as a core for the coil.

When the coil has been wound to the desired size, the driving clutch is disengaged to stop the block. Tie wires are then placed around the coil by inserting them through slots 18, 20, 30, 25 and 31, after which nut 23 and outer side plate 22 are removed. This permits collapse of the segments, facilitating removal of the coil from the block. When the completed coil has been removed, replacement of the side plate 22 and nut 23 effect outward radial movement of the segments as the nut is turned home tightly and the block is then ready for winding the next coil.

The block of our invention has the advantage

of simplicity of construction and ease of operation. It is particularly adapted, furthermore, for small sizes, i. e., such as to accommodate wire coils less than one foot in diameter. In addition, the construction requires little or no maintenance since the moving parts are few and their movement quite limited.

Although we have disclosed herein the preferred embodiment of our invention, we intend to cover as well any change or modification therein which may be made without departing from the spirit and scope of the invention.

We claim:

1. A take-up block comprising a mandrel adapted to be journaled on the end of a drive shaft with one end free to permit removal of a coil wound thereon, a hub at the other end of the mandrel, a side plate rigid with said hub, a second side plate removably disposed on the mandrel adjacent the free end thereof, circumferential grooves in the inner faces of said plates, each groove being defined by a cylindrical outer surface and a frusto-conical inner surface intersecting the cylindrical surface, a plurality of separate segments spaced circumferentially about the mandrel extending between the side plates and having ends of frusto-conical shape on the interior extending into said grooves and engaging said inner surfaces, each of said segments having a tongue extending axially on the interior thereof toward one end of the segments, a retainer ring fitted on the mandrel adjacent said one end of the segments, said ring surrounding said tongues and loosely confining the segments, and means for drawing said second side plate toward the first-mentioned side plate to cause outward radial movement of said segments.

2. A take-up block as defined by claim 1 characterized by said tongues being formed by arcuate slots on the interior of said segments adjacent to and opening toward one end thereof, said ring having a cylindrical flange fitting loosely in said slots.

DANIEL REVAK.
FREDERICK W. RIEDEL.
